Murry N. Fairbank, Weston, and Harold A. Marsh,
Boston, Mass., assignors to Polaroid Corpora-
tion, Cambridge, Mass., a corporation of Dela-
ware

Application August 14, 1943, Serial No. 110,917

Term of patent 14 years

(Cl. D57—1)

To all whom it may concern:

Be it known that we, Murry N. Fairbank and Harold A. Marsh, citizens of the United States and residents, respectively, of Weston, in the county of Middlesex and State of Massachusetts, and of Boston, in the county of Suffolk and State of Massachusetts, have invented a new, original, and ornamental Design for Binoculars, of which the following is a specification, reference being had to the accompanying drawing, forming part thereof.

Figure 1 is a perspective view from the eye-piece end of a pair of binoculars embodying the design of the present invention; and

Fig. 2 is a similar view taken from the objective end of the binoculars.

We claim:

The ornamental design for binoculars, sub-
stantially as shown.

MURRY N. FAIRBANK.
HAROLD A. MARSH.
